WILLIAM CHAMBERS, OF NEW ORLEANS, LOUISIANA.

Letters Patent No. 105,172, dated July 12, 1870.

IMPROVED COTTON-BALE TIE.

The Schedule referred to in these Letters Patent and making part of the same.

I, WILLIAM CHAMBERS, of the city of New Orleans, State of Louisiana, have invented a certain Improvement in Cotton-Bale Ties for fastening together the ends of metallic bands or hoops around bales of cotton, of which the following is a specification.

It is well known that, in the use of metallic bands in the operation of banding bales of cotton, one great difficulty is to take up the slack of the bands, so as to make all the bands of equal length, and the tension on each the same. It is, in fact, simply impossible to do this when the ends must be passed through the buckle and then bent under to secure the connection of the same, which must necessarily be done in all cases wherein the aperture or slot in the buckle that is employed is enveloped by an unbroken continuity of metal.

The result of this difficulty is, that the bale, when withdrawn from the compressing-machine, expands or bulges out in places, and hence presents a form not only completely wanting in regularity and symmetry, but which is also very inconvenient whenever a number of bales is to be stowed in vessels, warehouses, &c.

Another serious difficulty in the use of most existing cotton-bale ties grows out of the fact that one or both the surfaces of the buckle upon which the strain falls, in consequence of the thinness of the plate of which they are made, are so narrow that the flexure or fold of the bands, which is necessary to form the hooks at the extremities thereof, to establish the fastening, is so abrupt that the strength of the metal is impaired to such an extent that the bands frequently yield at that point under the enormous tension to which they are subjected, through the energy of the expansive force resulting from the elastic properties of cotton under compression, especially if the bale be subjected to any sudden shock or concussion.

The object of my invention is to remedy both these evils, and, in order to effect this object, I so construct my buckle or tie that the last end of the band that is fastened to the buckle may be folded into the form of an oblate hook before it is inserted therein. This secures a uniform length as to all the bands, and the taking up of all the slack.

Furthermore, in the construction of my buckle, I provide irregularly-formed expanded bearings for each end of the band, and thus avoid the necessity of making such an abrupt flexure of the latter that the integrity of the metal is injured, and, at the same time, secures a vertical depression of the metal below the plane of the plate, which, in connection with the irregularly-formed bearing surfaces, interposes an effectual check against the slipping of the band, which very often occurs when the bearing surfaces are smooth and round.

On the drawing—

Figures 1 and 2 represent my invention in perspective, and, by an edge view, the mode in which I prefer to connect the band thereto, in actual practice, being shown at fig. 1.

At Figures 3 and 4 my invention is shown by similar views, as when modified by a flexure or bend of the plate in its center, so as to have one of the bearings sufficiently below the plane of the other to leave a space equal to the thickness of the band between the upper and lower surfaces of the two.

A is the buckle, as a whole, which should be of the ordinary size, and made of wrought or cast-iron, and B B' two slits to receive the ends of the bands.

One of these slits, B, is completely enveloped by metal, while the other B' communicates with a cleft or narrow opening, C, that leads through the enveloping-rim, as shown. This cleft allows of the introduction of the last end of the band that is fastened to the buckle, after it has been bent into hook-form, and thus provides for the equal length of all the bands on a bale; but, separately considered, it is not a new device, nor do I lay any claim to it, irrespective of the other meritorious features of my invention, nor otherwise than in association with the latter.

This feature consists of an irregular expanded bearing for each end of the band, which I produce, in the stamping of the buckle, by a downward depression of those portions of the plate which are cut away, in order to make the slots B B', as shown at D D'.

These depressions present irregular bearing surfaces and a salient edge at the lower corners of their extremities, which, in the practice of the invention, press with great force against the band, and thus prevent its slipping, however great the tension.

I am aware that bearings, of curved form, of greater width than the thickness of the plates of which cotton-ties are formed, at least for one end of the band, are not new, any more than openings similar to C, and, furthermore, that projecting lips, from the central bar in ties, in which two slots obtain, are very common, but they are intended to make the tie self-fastening, and I do not claim either the one or the other; but

What I do claim as my invention is—

The combination of a cleft, C, in a cotton-bale tie or buckle, having two slots, B B', with two expanded bearing surfaces, D D', for the two ends of a metallic band, when the said bearing surfaces are produced in the manner herein described.

W. CHAMBERS.
